UNITED STATES PATENT OFFICE.

HORACE B. ROBINSON, OF WATERBURY, CONNECTICUT.

BUTTON.

SPECIFICATION forming part of Letters Patent No. 355,029, dated December 28, 1886.

Application filed October 21, 1886. Serial No. 216,841. (No model.)

To all whom it may concern:

Be it known that I, HORACE B. ROBINSON, a citizen of the United States of America, residing at Waterbury, in the county of New Haven and State of Connecticut, have invented 5 certain new and useful Improvements in Buttons, of which the following is a specification, reference being had therein to the accompanying drawings.

10 This invention relates to improvements in buttons; and it consists in the construction and arrangement of the parts, whereby the manufacture is simplified and the construction strengthened.

15 In the drawings, Figure 1 is a sectional view of my improved button. Fig. 2 is a section of the shell of the button. Figs. 3, 4, and 5 are detail views of the center of the button. Fig. 6 is a plan view of the button. Fig. 7 is 20 a section of an alternative form of the button.

The letter A designates the shell of the button, which is ribbed at A' and the edge rolled to form A³. The center is perforated at C, and countersunk so as to form the well B. The perforation C is then turned into the well 25 B, forming around the center the rib A³.

20 Into the well B is set the eyelet D, the flange of which is made to fit the said well, and the shank D' the perforation C. The shank D' is provided with slots cut in sides opposite. Into these slots is set a small pin, E, which 30 protrudes through the slots and rests on the edge of the perforation C, reaching nearly to the wall of the well B to prevent displacement.

35 When the parts are in this position, the ends of the shank D protrude through the perforation C. These are turned back on the edge A³, substantially as shown in Fig. 1 of drawings.

40 When the form shown in Fig. 1 is made, the eyelet D, carrying the pin E, is set in place, and

the ends of the shank D' are turned over the edge A³. The back F is then placed upon the shell, with the part F' corresponding to the well B and the edge covering the edge A³ and 45 turned ends of the shank D', and the edge of the shell is rolled upon it, substantially as shown.

In constructing the button the shell is rolled and ribbed, substantially as shown. The pin E 50 is placed in the slots provided in the shank D' of the eyelet. The eyelet bearing the pin is placed in the well B of the shell, with the ends of the shank protruding through the perforation C, and the ends of the shank D are turned 55 back upon the edge A³ of the shell, thus forming a button at once simple of manufacture and strong of construction.

It is obvious that I do not confine myself to the exact construction herein shown, as an eyelet might be used that is perforated, and the pin passed through such perforations before placing the eyelet in the well. 60

What I claim is—

As a new article of manufacture, a button 65 consisting of a shell the center of which is depressed to form a well, said well having an inwardly-extending flange around its lower edge, an eyelet provided with a slotted shank, the ends of which protrude beyond the flange 70 of said well and are turned back on the same, and a bar adapted to fit the slots of the said shank and to lie across said well and rest against the opposite walls thereof, substantially as described.

75 In testimony whereof I affix my signature in presence of two witnesses.

HORACE B. ROBINSON.

Witnesses:

W.M. W. BONNETT,
FRANKLIN L. WELTON.
